UNITED STATES PATENT OFFICE

2,558,715

MULTICOMPARTMENT FOLDING CARTON

Marshall I. Williamson, New Haven, Conn., assignor to National Folding Box Company, Inc., New Haven, Conn., a corporation of Connecticut

Application April 21, 1950, Serial No. 157,195

7 Claims. (Cl. 224—48)

1

This invention relates to improvements in boxes or cartons made from foldable sheet material, such as paperboard, for packaging in compartments or cells a plurality of bottles, cans, jars, or other articles as a unit which may easily be stacked by the dealer, carried home by the consumer, and which, in addition, provides a protection for the individual articles packaged therein.

Boxes or cartons of the aforementioned multi-compartment type have a wide variety of uses, one of the most common applications being the bottle carrier. The present invention will be explained hereinafter in its specific application to bottle carriers, although it is plain that the invention is equally applicable to the packaging, in multiple, of other products or articles of merchandise.

The invention provides a multi-cellular box or carton which may be produced from a minimum of board, which may be glued on conventional folding and gluing machines, and be set up by a few simple folding operations.

The invention relates more particularly to multicellular boxes of the type in which individual cells or pockets are formed by webs extending from one side wall to an opposite side wall or from one side wall to a central partition and thence to an opposite side wall, the webs extending substantially at right angles to the side walls and substantially normal with respect to the bottom of the box.

The invention provides a web structure resulting in the formation of substantially circular or polygonal cells, adapted to hold round articles with a snug grip without, however, making difficult the loading of the box with merchandise. The webs are of a particularly strong truss construction which makes them particularly suited for attachment thereto of handles made sheet material, for example, strap handles of paper-board by which the loaded box may be lifted up.

The cellular web structure is furthermore so designed that it may easily be set up from a flat, collapsed tubular blank structure and thereafter securely remains in set up condition. It resists accidental recollapsing or even distortion by reason of an unusual degree of stiffness. This feature makes the invention particularly valuable for bottle carriers which are to be loaded on automatic loading machines of the type in which a great number of bottles is simultaneously dropped into a plurality of pockets or cells. Resistance to deformation and the prevention of accidental collapsing is most important in bot-

2

tle carriers which are to be loaded on automatic machinery.

The various features, objects and advantages of the invention will appear more fully from the detailed description which follows accompanied by drawings showing, for the purpose of illustration, an application of the invention to bottle carriers. The invention also consists in certain new and original features of construction hereinafter set forth and claimed.

Although the characteristic features of the invention which are believed to be novel will be particularly pointed out in the claims appended hereto, the invention itself, its objects and advantages and the manner in which it may be carried out may be better understood from the detailed description in which:

Figure 1 is a plan view of a flat blank of a carrier body incorporating the present invention;

Figure 2 is a plan view of the blank of Figure 1 after an initial gluing and folding operation resulting in a flat tubular structure;

Figure 3 is a perspective view of the glued blank of Figure 2 after expansion into hollow form;

Figure 4 is a perspective view of the expanded blank of Figure 3 in the process of formation of its cellular top web structure;

Figure 5 is a perspective view of the completed carrier body after formation of its top web structure;

Figure 6 is a plan view of the completed carrier body shown in Figure 5;

Figure 7 is an elevational side view of the carrier body shown in Figure 5;

Figure 8 is a plan view of a flat blank for a suitable strap handle for the carrier body;

Figure 9 is a plan view of the blank shown in Figure 8 after reinforcement by staples;

Figure 10 is a side view, on an enlarged scale, of one of the ends of the strap shown in Figure 9 bent for attachment to a carrier body;

Figure 11 is a perspective view of a carrier assembled from the blanks shown in Figures 1 and 9;

Figure 12 is a plan view of a flat blank for a six cell carrier having a center partition; and

Figure 13 is a perspective view of the six cell carrier with an attached strap handle.

In the following description and in the claims various details will be identified by specific names for convenience. The names, however, are intended to be as generic in their application as the art will permit. Corresponding reference characters refer to corresponding parts in the several figures of the drawings.

In the drawings accompanying and forming part of this specification, certain specific disclosure of the invention is made for the purpose of explanation of broader aspects of the invention, but it is understood that the details may be modified in various respects without departure from the broad principles of the invention and that the invention may be applied to other structures than the ones shown.

The blank A as shown in Figure 1 may be cut and scored, in multiple, from large rolls or sheets of foldable sheet material such as paperboard, on automatic cutting and scoring machines. The several constituents parts of the blank are set apart by fold or crease lines. The blank comprises a side wall panel 11, a top wall pane 12, a further side wall panel 13, a bottom wall panel 14 and a glue lap 15 hingedly interconnected along fold lines 16, 17, 18, and 19, respectively. Elongated apertures 20 and 21 are cut in the top panel 11 for attachment of the handle, as will later appear.

The top panel 12 and adjoining portions of the side wall panels 11 and 13 are cut and scored to provide a cellular web structure forming individual compartments for bottles or other forms of merchandise. Cuts 22, 23 and 24 extend at right angles to the fold lines 16 and 17. These cuts separate the stock into webs 25, 26, 27 and 28 which after appropriate folding form article receiving cells, as will later appear.

The webs are foldable at a plurality of fold lines. These fold lines include diagonal or oblique fold lines 29, 30, 31, 32, 33 and 34 extending from short terminal cuts 35, 36 and 37 to the transverse fold line 17 at an angle. Similar diagonal fold lines 38, 39, 40, 41, 42 and 43 extend from similar short terminal cuts 44, 45 and 46 to the transverse fold line 16 and preferably include between themselves the same angles as the fold lines 29, 30, 31, 32, 33 and 34. The webs 25 and 28 constitute terminal webs since they lie at the outer edges of the blank. The webs 26 and 27 constitute intermediate webs. These intermediate webs comprise ridge fold lines 47 and 48 to provide for double ply thickness of the intermediate webs, as will later appear.

Folding of the web structure is facilitated by a plurality of crease lines 49, 50, 51, 52, 53, 54 and 49', 50', 51', 52', 53', 54'. These crease lines criss-cross the top panel 12 and subdivide the several webs into individual web portions. It is evident that the angles at which these crease lines intersect, as well as their outline, depends on the width of the panel 12 measured between the fold lines 16 and 17 as well as the depth or height of the respective webs in the finished carrier body. Further transverse fold lines 55 and 56 extend across the blank to facilitate folding of the webs as will later become apparent.

Triangular panels 57, 58, 59, 60 and 61, 62, 63 and 64 extend with their apexes from either end of the ridges of the webs. These ridges, as will later appear, are formed by the ridge fold lines 47 and 48 and by the outer edge portions of the outer edges 65 and 66 of the blank A. The triangular panels are bounded by the transverse fold lines 17 and 16, respectively, forming the bases of the triangles, and by further fold lines 67, 68, 69, 70, 71, 72 and 73, 74, 75, 76, 77 and 78, forming the sides of the triangles.

The assembly of the carrier body from the blank A may proceed as follows:

Adhesive *a* is first applied to the terminal glue lap 15 and the blank is folded about the fold line

18 to bring the panel 14 face-to-face with the panel 13. Thereafter the blank is folded about the fold line 19 and the terminal portion of the panel 11 is pressed into adhesive engagement with the glue lap 15. The resulting tubular structure A' is shown in Figure 2 and is ready for expansion into hollow form. Flat tubular blanks may be stored and shipped to the user in flat collapsed condition, requiring a minimum of space and may be set up into final form by a few relatively simple assembly operations which may be performed at the bottling plant. These operations will now be described.

The tubular blank A is first squared to assume a substantially rectangular shape as shown in Figure 3. Article receiving cells 79, 80 and 81 are then formed, and the blank is fixed in expanded position by exertion of force in the direction of arrows F against the several web panels 25, 26, 27 and 28. This force causes the web panels to move towards a vertical position with respect to the bottom panel 14. Simultaneously the ridges 65, 47, 48 and 66 are raised and the triangular panels 57, 58, 59, 60 and 61, 62, 63 and 64 assume a slanting position as shown in Figure 4. Further pressure against the web panels and supplementary pressure against the tilting edges 16 and 17 causes the web panels to assume their final vertical position which they then automatically maintain due to a peculiar behavior inherent in the illustrated structure which may be compared to the action of the commonly known over-center spring which snaps into one or the other of two extreme positions after being forced past its center position. A center position is encountered in the present assembly between the positions of the edges 16 and 17 in Figures 4 and 5 respectively, and the aforementioned supplemental pressure exerted against these edges causes the web assembly to snap into the position shown in Figure 5.

The carrier body thus formed is extremely rigid and resistant to deformation due to the truss-like construction of the webs dividing the cells 79, 80 and 81 from one another.

Figures 6 and 7 show the completed carrier body in plan view and in end view, respectively. It is apparent from both figures that the upper portions of the side walls 11 and 13 slope inwardly adjacent the webs, and this inward slope then continues, in the manner of a mansard roof, in the triangular panels 57, 58, 59, 60 and 61, 62, 63 and 64 from whose apexes the horizontal ridges 65, 47, 48 and 66 extend.

The sloping of the side walls is produced by the folding of the webs into a position substantially normal with respect to the bottom panel 14. As the ridges 65, 47, 48 and 66 are being raised above the fold lines 16 and 17, whereby also the triangular panels 57, 58, 59, 60 and 61, 62, 63 and 64 assume an upward slant, the side walls 11 and 13 are drawn together at the fold lines 16 and 17. It will be noted that the space between the side walls 11 and 13 becomes increasingly narrower as the V-shaped gaps 29 and 30, 31 and 32, 33 and 34 in the wall 13, and the corresponding gaps in the opposite wall 11 are becoming increasingly wider. The peculiar web construction thus provides a secure and snug seat for articles in the cells not only at the bottom of the V-shape gaps, but also at points above, where round articles would tend to encounter a loose fit, if the side walls were straight.

It is apparent that each of the webs comprises a central portion 97 and end portions 98. An intermediate portion lies between the central por-

terminal webs, since they lie at the outer edges of the blank. The webs 126 and 127 constitute intermediate webs. These intermediate webs comprise ridge fold lines 147 and 148 for double web thickness of the intermediate webs.

Folding of the web structure is facilitated by a plurality of crease lines 149, 150, 151, 152, 153, 154, and 179, 180, 181, 182, 183, and 184. These crease lines criss-cross the top panel 105 and subdivide the several webs into individual web portions. It is evident that the angles at which these crease lines intersect, as well as their outline, depends on the width of the panel 105 measured between the fold lines 111 and 112 as well as the depth or height of the respective webs in the finished carrier body. Further transverse fold lines 115 and 156 extend across the blank to facilitate folding of the web structure.

Triangular panels 157, 158, 159, 160 and 161, 162, 163 and 164 extend with their apexes from either end of the ridges of the webs. The ridges are formed by the ridge fold lines 147 and 148 and by the outer edge portions of the outer edges 165 and 166 of the blank A. The triangular panels are bounded by the transverse fold lines 111 and 112, respectively, forming the bases of the triangles, and by further fold lines 167, 168, 169, 170, 171, 172 and 173, 174, 175, 176, 177 and 178, forming the sides of the triangles.

Lock flaps 185 and 186 are cut from the stock of the center partition 102 and are hingedly connected thereto along fold lines 187 and 188, respectively. The fold lines 187 and 188 are preferably interrupted by cuts 192 and 193 forming extension tabs 194 and 195 integral with the flaps 185 and 186.

The lock flaps 185 and 186 fit into apertures 196 and 197 between the two plies of the intermediate webs 126 and 127. The apertures 196 and 197 are preferably so shaped as to form tabs 198 and 199 which fit into the apertures open at the fold lines 187 and 188, when the flaps 185 and 186 are folded into a position at right angles with respect to the plane of the center partition panel 102.

Apertures 115, 116, 117 and 118 are provided in the intermediate webs for engagement with the handle bars, as hereinbefore described.

In the set up carrier the lock flaps 185 and 186 rest between the two plies of the intermediate webs and maintain the partition panel 102 centered with respect to the webs 126 and 127. In this position the tabs 198 and 199 engage the apertures exposed by tabs 194 and 195 at the fold lines 187 and 188.

The invention thus provides a sturdy and efficient multi-compartment folding box particularly suited for the packaging in multiple of bottles, cans, jars, and other forms of merchandise. The box is attractive and requires a minimum of stock. Its folding and setting up operations are relatively simple and its strength is great which makes the box suited for repeated reuse.

What is claimed is:

1. In a folding carton for a plurality of bottles, cans, and other articles, the structural unit made from a blank of foldable sheet material, spaced portions of the blank being secured together to form a tubular structure including a plurality of creases between the several constituent parts of the unit, such parts comprising a bottom, side walls articulated to, and upwardly extending from, said bottom, and a top structure consisting of webs integral with said side walls

and extending from one side wall to the other to form cells between them for the reception of articles, each web having two end portions folded back upon the respective side walls about diagonal fold lines and overlying the side walls on the inside of the cell, said webs further including a central portion extending substantially at right angles to said side walls and substantially normal to said bottom, and an intermediate portion between the central portion and each end portion, said intermediate portion comprising a top panel articulated to the respective side wall and extending at an upward slant therefrom, and a substantially vertical skirt panel articulated to the respective end portion, the central portion and said top panel, respectively.

2. In a folding carton for a plurality of bottles, cans, and other articles, the structural unit made from a blank of foldable sheet material, spaced portions of the blank being secured together to form a tubular structure including a plurality of creases between the several constituent parts of the unit, such parts comprising a bottom, side walls articulated to, and upwardly extending from, said bottom, and a top structure consisting of webs integral with said side walls and extending from one side wall to the other to form cells between them for the reception of articles, each web having two end portions folded back upon the respective side walls about diagonal fold lines and overlying the side walls on the inside of the cell, said webs further including a central portion extending substantially at right angles to said side walls and substantially normal to said bottom, and an intermediate skirt portion articulated to the central portion and the respective end portion, said skirt portion extending substantially normal to the bottom and at an angle with respect to the central portion and to the end portion to which it is articulated, and a substantially triangular top portion articulated to said skirt portion and to the adjacent side wall and extending at an upward slope therefrom, said central portion adjoining the apex of the triangular portion.

3. A folding carton for a plurality of bottles, cans, and other articles, the carton being made from a blank of foldable sheet material, spaced portions of the blank being secured together to form a tubular structure including a plurality of creases between the several constituent portions of the carton, such portions comprising a bottom, side walls articulated to, and upwardly extending from, said bottom and a top structure consisting of webs integral with said side walls and extending from one side wall to the other to form cells between them for the reception of articles, each web having two end portions folded back upon the respective side walls about diagonal fold lines and overlying the side walls on the inside of the cell, said webs further including a central portion extending substantially at right angles to said side walls and substantially normal to said bottom, and an intermediate portion between the central portion and each end portion, said intermediate portion comprising a top surface articulated to the respective side wall and extending at an upward slant therefrom, and a substantially vertical skirt surface articulated to the respective end portion, the central portion and said top surface, respectively, the outermost webs of the carton being of single thickness, the webs lying between the outermost webs being of double thickness, the two thicknesses of the central por-

tion 97 and each end portion. This intermediate portion is composed of a triangular panel and a skirt portion 99. The skirt portion is articulated to the triangular panel and is integral with the central portion 97. The skirt portion 99 may be considered a connecting portion between the respective end portion 83 and the central portion 97 and extends at an angle to both.

The webs possess a surprising amount of strength and rigidity to a lifting force applied at their lower edges, particularly the webs 26 and 27 which are of double ply thickness. This feature makes the carrier body admirably suited for use with handles a preferred form of which will now be described. The handle forms the subject matter of a copending application for letters patent Serial No. 134,889 filed Dec. 24, 1949 of Marshall I. Williamson.

Referring to Figure 8, the flat strap handle blank B consists of a central hand grip portion 82 and end portions 83 and 84 foldably connected to the central portion 82 along fold lines 85 and 86. The central portion 82 of the blank B may include a plurality of scores 87 to facilitate subsequent flexing of the handle into U-shape. However, the scores 87 are not indispensable and may be omitted.

The blank B is made from paperboard, preferably board having substantial tear strength. Kraft is suitable stock for the handle. Ordinarily it can be used in single ply strength without any reinforcement. However, if the handle is to be used under particularly unfavorable conditions, if the load is exceptionally great, or if it is desired to use stock of lower grade for the handle, the blank B may be made of laminated stock, particularly stock including a fabric ply.

The shape of the blank B is optional. It may be made of equal width throughout, or, as shown in Figure 8, the portion 82 may be made progressively narrower towards the center for more convenient gripping of the strap by hand. It is preferable, although not necessary, to make the ends equal to the width of the panels 26 and 27, as measured between the fold lines 55 and 56.

The ends of the handle blank B are first reinforced by one or a plurality of metal staples at each end. The number of staples depends on the load to be carried, the width of the handle, and the gauge of the staple employed. In the illustrated form of handle two staples are used at each end. The staples 88, 89, 90 and 91 extend across the fold lines 85 and 86 respectively, and are preferably struck so that the ends of the staples within the end panels 83 and 84 are fully bent back or into the board, while the other ends of the staples are bent to remain at an angle with respect to the board to form a barb 92 as shown in Figure 10 illustrating one end of the handle B' after bending into hoop shape at the fold line 86. The portion of the staples within the end panel 84 is preferably shorter than the portion within the panel 82 to produce a tighter grip on the transverse web of the carrier body.

The assembly of the strap handle B' with the carrier body A'' is simple and may be performed as follows:

The blank of the handle B is first flexed into substantially inverted U-shape, and is then hooked onto the webs 26 and 27 of the carrier body as shown in Figure 11. The barbs engage the apertures 20 and 21 in the webs and prevent subsequent disengagement of the handle from the carrier body. The load is sustained by the handle at the fold lines 85 and 86 which is in a sur-

face-to-edge engagement with the lower edges of the transverse webs 26 and 27. The load tends to unbend the handle at the fold lines 85 and 86 which is effectively opposed by the stiffness of the staples 88, 89, 90 and 91 which thus serve the dual purpose of reinforcing the handles at critical points with regard to tear strength, and of adding to the stiffness of the handle at the same portions.

The assembled carrier body and handle shown in perspective in Figure 11. For convenience of stacking loaded carriers the handle may be depressed into a position below the tops of bottles in the carrier. Pressure against the top of the handle causes the handle to flatten out slightly at the top. This deformation, however, does not cause the handle to become disengaged from the transverse webs 26 and 27 nor the barbs to be withdrawn from the apertures 20 and 21. The end portions 83 and 84 of the handle are maintained in their handle securing position not only by the staples, but also by the pressure of bottles or other articles within the pockets 79, 80 and 81 bearing against the handle end portions 82, 83 and 84, respectively. The pressure of the bottles makes it obviously impossible for the handle to become disengaged from the carrier body under load. This is a safety feature of the construction.

A carrier for six bottles, cans, or other articles is shown in Figures 12 and 13. The construction of the carrier body B'' is very similar to that of the carrier body A'' except for the presence of a center partition 102 which divides the space between the webs 125, 126, 127 and 128 into six pockets. The webs 126 and 127 are of double ply thickness and include apertures 115, 116, 117 and 118 (Figure 12) similar to the apertures 20 and 21 in the carrier body A'' for engagement by the barbs of the handle 93. The barbs are formed by reinforcing staples in the same manner as shown in Figures 9, 10 and 11, the staples being visible at 189 and 191.

The handle 93 is of substantially the same outline as the handle B except for slits 95 and 96. The slits 95 and 96 facilitate the assembly of the handle 93 with the carrier body, in that the handle fits easily over the central partition 102.

The blank B of the carrier B'' is shown in Figure 12. It comprises a center partition 102, a bottom panel 103, side wall panel 104, a top panel 105, a further side wall panel 106, a further bottom panel 107 and a glue lap 108. These panels are hingedly interconnected along fold lines 109, 110, 111, 112, 113 and 114.

The top panel 105 and adjoining portions of the side wall panels 104 and 106 are cut and scored to provide a cellular web structure forming individual compartments for bottles or other forms of merchandise. Cuts 122, 123 and 124 extend at right angles to the fold lines 111 and 112. These cuts separate the stock into webs 125, 126, 127 and 128 which, after appropriate folding, form the article receiving cells.

The webs are foldable at a plurality of fold lines. These fold lines include diagonal or oblique fold lines 129, 130, 131, 132, 133 and 134 extending from short terminal cuts 135, 135 and 137 to the transverse fold line 111 at an angle. Similar diagonal fold lines 138, 139, 140, 141, 142 and 143 extend from similar short terminal cuts 144, 145 and 146 to the transverse-fold line 112 and preferably include between themselves the same angles as the fold lines 129, 130, 131, 132, 133 and 134. The webs 125 and 128 constitute

tion being folded back-to-back about a fold line forming the ridge of the web.

4. A folding carton for a plurality of bottles, cans, and other articles, the carton being made from a blank of foldable sheet material, spaced portions of the blank being secured together to form a tubular structure including a plurality of creases between the several constituent portions of the carton such portions comprising, a pair of outer side walls, a center partition having recesses cut into it from its top edge, a bottom connected to said side walls and said partition and a cellular top structure dividing the spaces between the side walls and the center partition into individual article receiving cells, said top structure comprising webs integral with said side walls and extending at substantially right angles to the side walls from one side wall to the other and transverse to said partition, each web having two end portions folded back upon the respective side walls about diagonal fold lines and overlying the side walls on the inside of the cell, said webs further including a central portion extending substantially at right angles to said side walls and substantially normal to said bottom, an intermediate skirt portion articulated to the central portion and the respective end portion, said skirt portion extending substantially normal to the bottom and at an angle with respect to the central portion and to the end portion to which it is articulated, and a substantially triangular top portion articulated to said skirt portion and to the adjacent side wall and extending at an upward slope therefrom, said central portion adjoining the apex of the triangular portion.

5. A folding carton set forth in the preceding claim 4 in which the top structure includes terminal webs lying at the ends of the carton and intermediate webs lying between the terminal webs, the intermediate webs having central portions of double thickness, the two thicknesses being folded back-to-back about a fold line forming the ridge of the web.

6. A folding carton for a plurality of bottles, cans, and other articles, the carton being made from a blank of foldable sheet material, spaced

45

portions of the blank being secured together to form a tubular structure including a plurality of creases between the several constituent portions of the carton such portions comprising, a pair of outer side walls, a center partition having recesses cut into it from its top edge, a bottom connected to said side walls and said partition and a cellular top structure dividing the spaces between the side walls and the center partition into individual articles receiving cells, said top structure comprising webs articulated to said side walls and extending at substantially right angles to the side walls from one side wall to the other and transverse to said partition, each web including a central portion extending substantially at right angles with respect to said side walls and through said recesses in said center partition and substantially upright with respect to said bottom, each web further including a substantially triangular portion articulated to each of said side walls and bordering said central portion with its apex, and downwardly depending skirt portions articulated to said triangular portions and to integral with said central portion.

7. A folding carton as set forth in the preceding claim 6 in which the top structure includes terminal webs lying at the ends of the carton and intermediate webs lying between the terminal webs, the intermediate webs having central portions of double thickness, the two thicknesses being folded back-to-back about a fold line forming the ridge of the web.

MARSHALL I. WILLIAMSON.
